ABSTRACT

Method for heating pressing plates of a continuous flat press for maintaining surface temperature thereof below 100° C. by utilizing steam. The inside pressure of a conduit disposed in said pressing plate is maintained at a predetermined pressure below an atmospheric pressure while supplying steam into said conduit. And it is preferably applied for carrying out the present method that the partial pressure of air in said conduit is discharged before supplying said steam into said conduit.

**METHOD FOR HEATING PRESSING PLATES OF
CONTINUOUS FLAT PRESS**

The present invention relates to an improved method for heating pressing plates of continuous flat press at a temperature below 100°C. by utilizing steam.

Generally, in the finishing process of textile fabrics such as worsted or woolen fabrics, certain union fabrics made of worsted or woolen yarn or blended yarn containing the same synthetic fibers, pressing of the fabrics must be applied for glazing, providing dimensional stability and improving hand feeling of the fabrics. It is well known that a "paper-pressing method" has been applied, for the above-mentioned purpose.

The paper-pressing operation applied to high-quality worsted fabrics is inevitable for attaining very elegant luster and good hand feeling. However, a fairly long time is required to complete the above-mentioned paper-pressing operation and moreover, the folds of the fabric are free from the paper-pressing operation. Therefore, in the paper-pressing operation, it is required to transfer the fabric, which has completed a first operation, to a lift table and at the same time, the insertion of the press papers are required to be changed.

For carrying out the above-mentioned paper-pressing operation in the conventional paper-pressing equipment, a plurality of presses and lifts are required to be used.

To eliminate the above-mentioned drawbacks involved in the paper-pressing method, a now well-known continuous flat press such as "Hattersley Pickard-Flat Press" was developed and these machines are now being practically applied for the continuous pressing operation. In a unit operation, a fabric is held by a pair of press plates under heat while one of the pressing plates is pushed to the other pressing plate by utilizing pneumatic or oil pressure, the fabric just completed in the pressing operation is moved forward by a predetermined distance while the pressing action by the two press plates is released. The above-mentioned operations are alternately carried out intermittently. By utilizing the above-mentioned continuous flat press, the pressing operation of the fabric can be carried out speedily and efficiently.

Generally, in the pressing operation of the fabric for providing luster thereof, pressure, temperature, humidity contained in the fabric, and operating time are very important factors to carry out the pressing operation. In these important factors, it is particularly required to control the temperature of the pressing operation. Heating of the pressing plates is carried out by supplying a heating medium into a heating conduit or conduits formed therein. In case the required temperature of the pressing plate is higher than 100°C., steam is used as the heating medium, while in case the required temperature is below 100°C., hot water is used as the heating medium. However, in the latter case, the surface temperature of the pressing plate is very difficult to maintain in a uniform condition, and it is required to supply the hot water with a high flow rate for preventing the irregular distribution of the surface temperature of the pressing plate.

The principal object of the present invention is to provide an improved heating method of the pressing plates of the continuous flat press wherein the pressing plates are always maintained at a uniform temperature below 100°C. with high heating efficiency.

Further features and advantages of the invention will be apparent from the ensuing description with reference to the accompanying drawings to which the scope of the invention is no way limited.

FIG. 1 is an explanatory diagram for illustrating the dropping of the temperature of the hot water supplied into a conduit formed in a pressing plate when the surface temperature of the pressing plate is maintained at a uniform, constant value,

FIG. 2 is a schematic diagram of a heating device applied to the pressing plate of the continuous flat press, according to the present invention.

For better understanding of the present invention, firstly, the drawback of the heating method applied to the conventional flat press is analytically illustrated.

Now, a conventional pressing plate maintaining its temperature at 95° C. by supplying hot water, is considered. The required quantity of heat for maintaining the pressing plate at 95° C. is supposed to be 7,000 Kcal./hour. In the above-mentioned condition, the following equation is obtained:

$$Q = C_p W \Delta\theta_3 = U A (\Delta\theta_1 - \Delta\theta_2) / (2.3 \log(\Delta\theta_1 / \Delta\theta_2)) \quad (1)$$

Where

Q: quantity of heat required to maintain the temperature of a pressing plate at 95° C.

U: heat transfer coefficient with respect to transmitting heat energy from the hot water to the pressing plate made of iron.

A: area of heat transmission of a conduit for flowing the hot water (dia. of the conduit = 22 mm.).

W: flow rate of the circulation of the hot water kg./hr.

C_p: specific heat at constant pressure Kcal./kg. °C.

$\Delta\theta_1$: difference between a temperature of the hot water at an entrance of the conduit and that of the pressing plate.

$\Delta\theta_2$: difference between a temperature of the hot water at an outlet of the conduit and that of the pressing plate.

$\Delta\theta_3$: difference between a temperature of the hot water at the inlet of the conduit and that at the outlet of the conduit.

25 The relation between θ_1 , θ_2 and θ_3 is shown in FIG. 1. Referring to FIG. 1, and assuming that the differential temperature $\Delta\theta_2$ is 4° C. with the following measured data: $Q=7,000$ Kcal./hr., $U=340$ Kcal./m.² hr. °C., and $A=1.3$ m.²; then,

$$\Delta\theta_1=40^\circ\text{C.}, \text{ and}$$

$$W=1,930 \text{ kg./hr.}=32.1 \text{ kg./min.}$$

As is clearly understood from the above-mentioned calculation, to maintain the pressing plate at 95° C. it is necessary to continuously supply hot water of 135° C. at a flow rate of 32.1 kg./min. In other words, the temperature of the hot water

35 supply is about 40° C. higher than that of the pressing plate, moreover, the flow rate of 32.1 kg./min. is a distinctly large quantity of hot water, which is a required supply for maintaining the temperature of the pressing plate at 95° C.

In fact, there is a certain limitation for enlarging the area *A* 40 of the heat transmission of the conduit, because of the construction of the pressing plate.

Therefore, it is required to make $\Delta\theta_1$ as large as possible for transmitting a sufficient quantity of heat *Q* from the hot water to the pressing plate. In other words, in the case of heating the pressing plate at 80° C. ~ 100° C. by utilizing hot water in a uniform condition, it is quite certain that a quantity of exchange heat between the hot water in the conduit and the pressing plate is insufficient for attaining the uniform condition of the pressing plate even though the difference between the temperature of the hot water at the inlet of the conduit and that at the outlet of the conduit is very large.

The principle of the present invention is based upon a fact that it is capable of heating the pressing plate uniformly by steam; provided that a pressure in the conduit formed in the pressing plate is properly adjusted. It is important that the capacity of the heat transmission of the steam, in other words, "value of *U*" is remarkably larger than that of the hot water.

Referring to FIG. 2 showing an embodiment of the device 60 for carrying out the present invention, steam of comparatively low pressure is supplied to a heat medium conduit 2 formed in a pressing plate 1 from a steam supply pipe 3. The steam supplied to the conduit 2 imparts heat to the pressing plate while passing through the conduit 2 so that the temperature of the pressing plate 1 becomes a predetermined level. Steam pressure in the conduit 2 is indicated by a pressure gauge 4. An outlet of the conduit 2 is connected to a steam trap 7 through a conduit 14 and a valve 6 mounted on the conduit 14 and further connected to an inlet of a pump 10 through a valve 8 and a pressure gauge 9. A bypass conduit 11 is connected to the conduit 14 as shown in FIG. 2, and a valve 12 is mounted on the bypass conduit 11.

The method for heating the pressing plate of the continuous flat press utilizing the above-mentioned device is hereinafter illustrated. As a first step, valves 5 and 6 are closed and the

valve 12 is opened. Next, the pump 10 is driven so that the partial pressure of air in the conduit 2 is decreased, until the air pressure becomes a predetermined value. Next, the valve 12 is closed and the valve 5 is opened so that steam is supplied into the conduit 2 while the pump 10 is continuously driven and the valves 6 and 8 are opened. In case the pressing plate 1 is heated at a temperature below 100° C., the inside pressure of the conduit 2 is maintained at a proper pressure below an atmospheric pressure. Since the supplied steam is condensed after imparting heat to the pressing plate 1, so that a drain liquid is produced inside the conduit 2, it is required to control the pressure in the conduit 14, as indicated at the pressure gauge 9 (hereinafter referred to as "secondary pressure"), so that the above-mentioned drain liquid can be discharged to the outside of the device through the steam trap 7. By our experimental tests, it was found that a primary pressure indicated by the pressure gauge 4 should be maintained at a pressure higher than a secondary pressure indicated by the pressure gauge 9 by at least 0.1 kg./cm.², preferably 0.3 kg./cm.². If the above-mentioned pressure difference is below 0.1 kg./cm.², it is impossible to discharge the above-mentioned drain and to maintain the surface temperature of the pressing plate 1 in uniform condition. It is recommended to use a Nash-type water sealing pump, which is capable of discharging the drain, as a decompression pump for carrying out the present invention. By utilizing the above-mentioned decompression pump, the remaining partial pressure of air is completely removed during the discharging operation of the drain through the steam trap 7, even though the partial pressure of air still remains in the conduit 2 after completion of the first operation for decreasing the partial pressure of air. In the above-mentioned operation, the drain is discharged from the drain discharging outlet 15, while air or steam is discharged from the discharging outlet 13.

As mentioned above, in case of carrying out the pressing operation by the continuous flat press in a temperature condition below 100° C., the heating method of the invention is ap-

plied to a decompression steam-heating method. In spite of using a long meandering conduit having small cross-sectional diameter, since the conduit is heated uniformly by the adiabatic compression effect by the supplied steam, the temperature in the entire conduit within the pressing plate becomes uniform if the pressure in the conduit is maintained in uniform condition. Therefore, the distribution of temperature of the pressing plate becomes very uniform. Therefore, by applying the above-mentioned heating method, according to the present invention, a long pending problem with respect to the drawback of the conventional flat press, which is illustrated in the preamble of this specification, can be completely solved. Consequently, a uniform flat-pressing operation can be carried out with high efficiency for pressing the high-grade worsted fabrics and various fabrics which require the operation at a temperature below 100° C., by applying the heating method of the present invention.

What is claimed is:

1. An improved method of heating a pressing plate of a continuous flat press provided with at least one conduit formed therein for flowing a heating medium through said flat press, and provided with a steam trap having an input connected to said conduit, and of maintaining said pressing plate at a predetermined temperature below 100° C., comprising the steps of discharging air from said conduit, supplying steam into said conduit, discharging said steam and drain liquid produced in said conduit from said conduit through said steam trap while maintaining the inside pressure of said conduit at a predetermined pressure below atmospheric pressure, and decreasing the pressure at an output of said steam trap to a pressure lower than said conduit pressure by at least 0.1 kg./cm.², thereby maintaining said pressing plate at a uniform predetermined temperature.
2. An improved heating method as set forth in claim 1, in which said steam trap output pressure is decreased to a pressure lower than said conduit pressure by at least 0.3 kg./cm.².
